UNITED STATES PATENT OFFICE.

HARTLEY BLYTH PRATT, OF BARROW-IN-FURNESS, ENGLAND, ASSIGNOR TO VICKERS LIMITED, OF WESTMINSTER, ENGLAND, A BRITISH COMPANY.

DEPTH CHARGE AND LIKE SUBMARINE EXPLOSIVE BODY.

Application filed October 1, 1925, Serial No. 59,808, and in Great Britain October 3, 1924.

This invention relates to depth charges and like submarine explosive bodies. More particularly the invention relates to so-called depth charges or like bodies which 5 are adapted to fire automatically on reaching a predetermined depth.

It has been proposed to fire such depth charges at a predetermined depth by means of hydrostatically operated mechanism and 10 one form of such mechanism involves the use of a timing device comprising a chamber into which water can flow at varying selected rates, the arrangement being such that the time taken to fill the chamber to the 15 required extent for operating the hydrostat and so firing the depth charge is equal to or substantially equal to the time taken for the body to sink freely to a specified depth, and the chief object of the present invention 20 is to provide a submarine explosive body the firing mechanism of which is directly operated by the hydrostatic pressure and independently of the speed or time taken for the depth charge to sink to the 25 desired depth.

According to the present invention the regulation of the firing depth is effected by varying the volume into which a quantity of trapped air is compressed. To this end a 30 quantity of air may be trapped between relatively movable parts, one or both said parts being acted upon by the hydrostatic pressure and the arrangement being such that automatic firing takes place when the 35 water pressure brings the relatively movable parts into correct relative firing position. The depth at which firing is adapted to take place may be controlled as desired by varying the capacity of an air space or spaces 40 so as to increase or diminish the volume of air initially trapped between the aforesaid relatively movable parts. Consequently the external water pressure (and hence the depth of sinking), which is required to fire 45 the explosive body will be that which is necessary to compress any particular volume of trapped air to the extent which is necessary to allow the relatively movable parts to reach the firing position.

50 In the case of a depth charge, the pistol and primer may be located within a tubular casing, and air may be trapped in said tubular casing between the pistol and the primer. The primer itself may be movable 55 under the influence of the hydrostatic pres-

sure so that it acts as a piston which will compress the air trapped in the said tubular casing. The primer is normally located some distance away from the pistol, and, after launching of the depth charge, and 60 under the influence of the hydrostatic pressure the primer will move forward along the tubular casing and compress the trapped air. When sufficient hydrostatic pressure is available to move the primer into correct 65 relative firing position with regard to the pistol, the pistol is automatically actuated and explodes the depth charge. Additional air spaces, suitably controlled by a valve or the like may also be provided one or more 70 of said air spaces being adapted to be placed in communication with the air space between the pistol and primer units so as to vary the firing depth.

In order that the said invention may be 75 clearly understood and readily carried into effect the same will now be described more fully with reference to the accompanying drawing, in which:

Figure 1 is a longitudinal section of a 80 depth charge constructed according to one embodiment of the present invention, the parts being shown in the position which they occupy prior to launching of the depth charge.

Figure 2 is a detail view of part of the 85 depth charge showing the primer and pistol in the firing position.

Figure 3 is a section on the line X—X of 90 Figure 1, and

Figure 4 is a view looking down on the 95 head of the piston and showing the depth indicating dial.

Figure 5 is a view corresponding to Figure 1 showing a modified construction of 100 depth charge, and Figure 6 is a detail view showing the depth indicating dial.

Referring to the embodiment of the invention shown at Figures 1 to 4, A is a guide tube located centrally of a main casing or 105 charge case B, which contains the bursting charge C, the guide tube A being welded at one end a directly to the charge case B, its other end being welded to a flanged part a² of the charge case. The primer D¹ is 110 located within a casing D (hereinafter termed the primer case) which is of cylindrical formation and slidably mounted within the guide tube A so as to act as a piston or plunger. Normally the primer case 110

D is located at one extreme end of the guide tube A (as shown at Figure 1), and, to hold it in this position up to launching of the depth charge, the primer case D may be provided with a projecting part d which extends through a bung or closure plate d¹ positioned within the guide tube A, the said bung or closure plate d¹ having openings d² for admitting water to the guide tube A. The primer case D is normally held in the position shown at Figure 1 by means of a safety pin d³ which engages a recess in the said projecting part d said pin d³ being removed before the depth charge is launched. An airtight joint between the primer case D and the guide tube A may be effected in any desired manner, for example, by providing a ring of rubber or other flexible material d⁴ between the primer case D and the guide tube A, said rubber ring d⁴ being adapted to allow the primer case D to move relatively to the guide tube A while at the same time preserving an air and water-tight joint. E is the pistol which is secured by bolts e to the flange a² so as to form an air-tight joint, and is located at the opposite end of the guide tube A. e¹ is a detonator which is mounted at the end of a tube e³ (hereinafter termed the detonator carrier) which projects into the guide tube A. The striker e⁴ is located within the detonator carrier e³ and said striker is provided with a flange e⁵, between which and a plug e⁶ a firing spring e⁷ is located. The detonator carrier e³ and the striker e⁴ are capable of relative sliding movement but such movement is normally prevented by means of suitable releasing devices, such for example as a so-called ball release, the laterally displaceable balls e⁸ being located within a slot in the detonator carrier e³ and projecting into a groove in the striker e⁴. Surrounding the striker e⁴ and the detonator carrier e³ is a casing e⁹ (hereinafter termed the striker casing), the detonator carrier e³ being provided with a flange at its inner end which flange is normally held against a shoulder e¹⁰ on the striker casing e⁹ by the striker spring e⁷. Positioned around the striker casing e⁹ in a hollow box-like part F (hereinafter termed the air chamber) which is divided into compartments f¹, f¹ of different sizes by means of division plates f, f. Air spaces are therefore provided and one or more of said spaces can be placed as desired in communication with the main air space G in the guide tube A by suitable means. For example a rotatable plate valve H may be provided which is formed with openings h which can be manipulated as desired to place one or more of the compartments f¹, f¹ in the air chamber F in communication, through passages f², f², with the air space G in the guide tube A. The plate valve H is positioned around the striker casing e⁹ and is held in contact with a flanged part f³ of the air chamber F by means of a spring I located between the plate valve H and a nut i on the striker casing e⁹. The part of the striker casing e⁹ which projects beyond the base of the depth charge may be provided with a pointer e¹⁰ and, on the contiguous part of the air chamber a scale or a series of calibrations f⁴ (Figure 4) may be provided so as to indicate the adjusted depth at which firing will take place. For example, when the air chamber F is not in use the air trapped in the space G between the primer case D and the plate valve H may be adapted to fire the pistol at a depth of 300 feet. Where for example and as shown at Figure 3 four compartments are provided in the air chamber P the arrangement may be such that when one of said compartments f¹ is added to the clearance volume G in the guide tube A the depth charge will fire at 200 feet; when another compartment is added the depth charge will fire at 150 feet; when a third compartment is added the depth charge will fire at 100 feet and when the fourth compartment is added the depth charge will fire at 50 feet. Regulation of the volume of trapped air, or in other words the number of compartments added to the clearance volume in the guide tube A, is effected by rotating the plate valve H by means of a key applied to the part e¹⁴ on the end of the striker casing e⁹. The striker casing e⁹ is provided with splines e¹¹ which engage the plate valve H so as to cause the latter to turn with the striker casing e⁹. When the pointer e¹⁰ on the striker casing e⁹ is brought opposite a calibration corresponding to a particular depth the required openings h in the plate valve H will register with the requisite passage or passages f², f² communicating with an appropriate compartment f¹ or compartments f¹, f¹ in the air chamber F. The rotation of the striker casing e⁹ and consequently the plate valve H may be controlled by means of a detent e¹² provided either at the base of the air chamber or (as shown) on the pointer e¹⁰ carried by the striker casing e⁹ the detent e¹² being held within a seat either on the air chamber or on the pointer by the pressure exerted by the spring I located between the plate valve H and the flange on the striker casing. By a forcible effort exerted by means of the aforesaid key the detent e¹² is lifted out of its seat and the striker casing e⁹ is turned and the detent will thereafter slip into the next seat corresponding to any particular calibration.

The primer case D, as aforesaid, is normally held at the top of the depth charge by means of a safety pin d³. When this safety pin is removed and the depth charge launched, water passes through the openings d² in the bung or cover plate d¹ and

the hydrostatic pressure acts on the outer end of the primer case D and also on the aforesaid rolling rubber ring d^4 . The primer case D is therefore pushed up the guide tube A and compresses the air between the inner end of the same and the plate valve H or the air compartments in the air chambers F if any of them have been opened. Leakage of air outwards or 10 water inwards is effectually prevented by the rolling rubber ring d^4 and accordingly the external water pressure and the internal air pressure will be substantially the same, the water pressure being slightly greater so 15 as to overcome the sliding friction of the rolling rubber ring d^4 . There is therefore no tendency for air to leak outwards and with the slight difference in pressure on each side of the rubber ring d^4 the latter 20 effectually prevents water leakage inwards. The pistol E as aforesaid, is adapted to fire after the hydrostatic pressure has pushed the primer case D up to the top of the guide tube A into a position where the 25 detonator e^1 projects into a recessed part d^5 in the primer case D. When the parts are in this position the detonator carrier e^3 is pushed along the striker e^4 and compresses the striker spring e^7 the compressing action 30 being continued until the balls e^8 of the ball release pass beyond the shoulder in the striker casing whereupon they move laterally outwards and disconnect the striker from the detonator carrier. The reaction of the 35 striker spring then forces the striker violently in contact with the detonator exploding the same and detonating the primer, and consequently exploding the main bursting charge. 40 In the modified arrangement shown at Figure 5 the same reference letters have been employed to designate the same or corresponding parts of the depth charge. In this embodiment of the invention, however, 45 two air chambers K^1 and K^2 only are provided in the pistol. The chamber K^2 is adapted to be placed into communication with the space G by a port k and the chamber K^1 is adapted to be placed into communication with the space G by means of a tube k^1 extending through the chamber K^2 , the port k and the tube k^1 being controlled as before by a rotatable plate valve H having ports h , h formed therein. The capacity of 50 these three air chambers G, K^1 and K^2 may be such as to provide for three depth settings, namely 60, 120 and 180 feet. For the 180 feet setting both the chambers K^1 and K^2 are closed off so that the clearance volume G in the guide tube A determines the firing pressure. For the 120 feet the volume K^2 is added and for 60 feet the volumes K^1 and K^2 are added. 55 If desired additional air chambers can also be provided if more depth settings are required. The adjusting mechanism for rotating the plate valve H comprises a nut H^1 secured to the striker e^4 the plate valve H being integral with or rigidly connected to the lower end of the striker e^4 so that it 60 rotates therewith. Splines F, F are provided between the rotatable nut and the casting within which the striker is adapted to rotate. The nut H preferably carries a pointer H^2 which serves the combined function of rotating the nut H and at the same time indicating the particular calibration on the dial H^2 to which the pointer has been 65 adjusted. To render the pistol safe when the pointer is set to the calibration "Safe" the part L is provided with a serrated flange L^1 and corresponding serrations M^1 , M^1 are cut in the body portion M. When the setting is at "Safe" the serrations L^1 are located opposite the serrations M^1 thus preventing movement of the part L and consequently preventing operation of the pistol release. When, however, the pointer H^2 is moved over to indicate a depth setting the serrations L^1 allow the part L to move through 70 the part M^1 . 75 Instead of providing a fixed pistol unit and a moving primer unit the primer can be fixed and the pistol unit can be adapted to move, or, alternatively both the pistol and primer units may be adapted to move inwards simultaneously so as to effect the explosion of the mine in the manner previously described. 80 85 90 95 100 What I claim and desire to secure by Letters Patent of the United States is:—

1. A depth charge or like submarine body comprising members movable relatively to one another under the influence of the hydrostatic pressure, means for automatically exploding the body when said members come into contact with one another and means for varying the volume of air compressed by said members in moving into contact with one another so as to vary the depth at which automatic firing takes place. 105
2. A depth charge or like submarine explosive body comprising members which are normally situated apart and between which a predetermined volume of air is trapped, said members being adapted to move towards one another under the influence of the hydrostatic pressure, means for trapping a predetermined volume of air between said relatively movable members and means for automatically firing the body when the hydrostatic pressure has compressed the predetermined volume of trapped air to the extent which is necessary to bring said relatively movable members into correct relative firing position. 115 120 125
3. A depth charge in which the automatic firing gear comprises a plurality of units which are movable into contact with one 130

another under the influence of the hydro-
static pressure and means for varying the
volume of air which is compressed by said
units in moving into contact with one an-
other so as to vary the depth at which auto-
matic firing takes place.

4. A depth charge or like submarine ex-
plosive body comprising two units which are
movable towards one another under the in-
fluence of the hydrostatic pressure, means
for trapping a predetermined volume of air
between said relatively movable units and
means for automatically firing the body
when the hydrostatic pressure has com-
pressed the predetermined volume of trapped
air to the extent which is necessary to bring
the said relatively movable parts into cor-
rect relative firing position.

5. A depth charge or like submarine ex-
plosive body comprising a tubular casing, a
pistol and a primer unit located within said
tubular casing, said pistol and primer units
being separated by an air space, means for
trapping a predetermined volume of air in
said air space, said primer unit being mov-
able under the influence of the hydrostatic
pressure so as to compress the air trapped
in said air space for the purpose specified.

6. A depth charge or like submarine ex-

plosive body comprising a tubular casing, 30
a pistol and a primer unit located within
said tubular casing, said pistol and primer
units being separated by an air space, means
for trapping a predetermined volume of air
in said air space, said pistol unit being 35
movable under the influence of the hydro-
static pressure so as to compress the air
trapped in said air space for the purpose
specified.

7. A depth charge or like submarine ex- 40
plosive body comprising a tubular casing, a
pistol and a primer unit located within said
tubular casing, said pistol and primer units
being separated by an air space within
which a predetermined volume of air is 45
trapped, both said units being movable un-
der the influence of the hydrostatic pressure
so as to compress the air trapped in said
air space for the purpose specified.

8. A depth charge or like submarine ex- 50
plosive body comprising a tubular casing,
pistol and primer units located within said
tubular casing, with an air space between
said pistol and primer units, and means for
placing additional air spaces in communi- 55
cation with the air space between said pistol
and primer units for the purpose specified.

HARTLEY BLYTH PRATT.
